UNITED STATES PATENT OFFICE.

HARRY RANDOLPH VAN DEVENTER, OF SUMTER, SOUTH CAROLINA, ASSIGNOR, BY
MESNE ASSIGNMENTS, TO SPLITDORF ELECTRICAL COMPANY, OF NEWARK, NEW
JERSEY, A CORPORATION OF NEW JERSEY.

IGNITER MECHANISM FOR INTERNAL-COMBUSTION ENGINES.

1,244,260.

Specification of Letters Patent.

Patented Oct. 23, 1917.

Application filed December 24, 1914. Serial No. 878,931.

To all whom it may concern:

Be it known that I, HARRY RANDOLPH VAN DEVENTER, a citizen of the United States, residing at Sumter, in the county of Sum-
5 ter and State of South Carolina, have invented certain new and useful Improve-
ments in Igniter Mechanism for Internal-
Combustion Engines, of which the follow-
ing is a specification, reference being had
10 to the accompanying drawing.

My invention relates to ignition apparatus for internal combustion engines, and has for its purpose the provision of a compact and efficient ignition unit, self-contained and
15 mounted upon or in close association with the igniter proper of the engine.

Briefly and specifically stated, this invention comprises a bracket mounted on or connected with the igniter, a flange or frame
20 also connected to the igniter, and carrying abutments outwardly extending from the engine cylinder, with a magneto mounted on the bracket, carrying an actuator on its rotor or oscillator shaft, said actuator being
25 connected by resilient or other energy storing means, such as coil springs, with the abutments or posts on the flange or frame. The actuator, being carried on the magneto, itself carries a projecting member which at
30 the proper instant in each actuation, acts upon the movable electrode of the igniter.

It is to be understood that the foregoing statement is made specific for purposes of definition and not of limitation. One of the
35 great advantages of this construction is its extreme simplicity, and the small number of parts required, while adhering to a high standard of efficiency. This unit is applicable to a great variety of internal combustion engines, and further advantages and features of invention will be sufficiently apparent to those skilled in the art, from the foregoing detailed description.

My invention is illustrated in the accompanying drawings in which:

Figure 1 is a top plan view.

Fig. 2 is a front view of Fig. 1 with the magneto removed and a portion of its shaft shown in section.

Fig. 3 is a left side view of Fig. 1, with the pull springs and parts of the engine removed for the sake of clearness.

In the drawings, a section of the engine cylinder is shown at 1 through which the

igniter body 2 projects into the combustion chamber. The igniter body 2, on the inside, carries a make-and-break contact device consisting of the fixed contact member 4 suitably insulated from the igniter body, and the movable contact 3 carried on the inner end of the igniter shaft 15, journaled in a bore passing through the igniter body. The igniter body is held in fixed relation with the engine by means of the flange 5 integral with said igniter body or otherwise rigidly connected therewith, which flange is provided with oppositely extending arms 6 and 7 and an outwardly extending support or bracket 25, for supporting the operating mechanism and the magneto. The 70 igniter shaft 15 extends through the igniter body and beyond the outer face of the flange 5 where it carries an actuating arm 22 at its outer end and a torsion spring 24 connected between the operating arm and the flange 75 in such manner as to normally tend to hold the igniter contacts closed or engaged. The magneto 26 is mounted on the bracket 25 with its rotor shaft 40 in alignment with the igniter shaft 15, the rotor shaft carrying, 80 in fixed relation thereto, a trip lever 14. This trip lever is held normally in the position shown by the pull springs 12 and 13 held at their outer ends on roller bearings 10 and 11 journaled at the outer ends of the 85 posts 8 and 10 which in turn are carried by the arms 7 and 6, respectively, the inner ends of the pull springs taking hold of the trip lever through the roller bearings 41 and 42. The right hand arm of the trip 90 lever 14 carries a firing finger 16 whose motion is transmitted to the igniter operating arm 22 through an adjustable abutment screw 23 threaded into the end of the operating lever. Movement of the trip lever 95 14 is effected by means of the trip finger 18 forming a part thereof and adapted to be engaged by the end 21 of the push rod 19 and rotated counter-clockwise against the tension of the pull springs until the end 100 of the push rod moves out of the arc scribed by the finger 18, whereupon it is suddenly returned to the normal position shown, by the power stored in the pull springs. The 105 operation of the push rod is accomplished by connecting it with a movable part of the engine in a well known manner. Each time the trip lever is suddenly released, in the

manner just described, the firing pin 16, in its return movement, strikes the lower end of the abutment screw 23 rotating the igniter actuating arm 22 and shaft 15 in a clockwise position against the tension of the torsion spring 24 which moves the contact 3 of the igniter up out of engagement with the fixed contact 4.

It is to be noted that the trip lever 14 is positioned on the rotor shaft 40 in such relation to the rotor and screw 23 so adjusted that when the trip lever is released the peak of the current wave generated will occur at the same instant that the igniter contacts 15 separate. Electrical connection is made between the windings of the magneto 26 and the fixed contact 4 by means of a suitable conductor 29 extending between the magneto binding post 30 and the igniter binding 20 post 31, the other arm of the circuit being the frame work as usual.

The timing of ignition is accomplished by the provision of an adjustable guide for the push rod 19, said guide consisting of the 25 roller bearing 20 mounted eccentrically on the shaft 36 and adapted to be adjusted angularly about said shaft by means of a handle 37. Thus the path of movement of the end 21 of the push rod may be raised or 30 lowered through different degrees, resulting respectively in a relatively early or late release of the trip lever, according to the adjustment of the handle 37, in a manner apparent.

35 It is further provided that the operation of the igniter shall be prevented during the idle stroke of the engine, as in the case of "hit-and-miss" engines, or when the exhaust valve is held open by the governor, by the 40 use of an independent lifting means for the push rod consisting of a bell crank lever 34 pivoted to the arm 6 and adapted to be moved into the dotted line position by the pin 33 on the exhaust valve push rod 32 45 which is actuated in a known manner at the intervals mentioned.

While I have herein shown and described in detail a preferred embodiment of my invention, it is to be understood that various 50 modifications thereof may be made without departing from the spirit of the invention, which modifications are contemplated by me.

Having thus described my invention, what

I claim and desire to secure by Letters Patent is:—

55

1. An igniter mechanism for internal combustion engines comprising a supporting frame, an igniter carried by said frame, a magneto mounted on said frame, an operating shaft for said igniter carried by said frame, an operating shaft for said magneto, said shafts being in alinement, a trip lever carried by the shaft of the magneto, an arm carried by the shaft of the igniter, means carried by the trip lever for engaging the arm carried by the shaft of the igniter, and means for actuating said trip lever.

60

2. An igniter mechanism for internal combustion engines comprising a supporting frame, an igniter carried by said frame, a magneto mounted on said frame, an operating shaft for said igniter carried by said frame, an operating shaft for said magneto, said shafts being in alinement, a trip lever carried by the shaft of the magneto, an arm carried by the shaft of the igniter, means carried by the trip lever for engaging the arm carried by the shaft of the igniter, and means for actuating said trip lever.

65

3. An igniter mechanism for internal combustion engines comprising a supporting frame, an igniter carried by said frame, a magneto mounted on said frame, an operating shaft for said igniter carried by said frame, an operating shaft for said magneto, said shafts being in alinement, a trip lever carried by the shaft of the magneto, an arm carried by the shaft of the igniter, means carried by the trip lever for engaging the arm carried by the shaft of the igniter, opposed springs connected to said trip lever and to said frame for actuating the magneto 80 shaft when said trip lever is released, and means for actuating said trip lever.

70

3. An igniter mechanism for internal combustion engines comprising a supporting frame, an igniter carried by said frame, a magneto mounted on said frame, an operating shaft for said igniter carried by said frame, an operating shaft for said magneto, said shafts being in alinement, a trip lever carried by the shaft of the magneto, an arm carried by the shaft of the igniter, means carried by the trip lever for engaging the arm carried by the shaft of the igniter, opposed springs connected to said trip lever and to said frame for actuating the magneto 85 shaft when said trip lever is released, said trip lever having a projecting arm, and a push rod for engaging said arm for setting and releasing the trip.

80

In testimony whereof I hereunto affix my 90 signature in the presence of two witnesses.

HARRY RANDOLPH VAN DEVENTER.
